OTHER PUBLICATIONS

Pending U.S. Appl. No. 14/486,180, filed Sep. 15, 2014, entitled Modular Display Unit, 30 pages.

(Continued)

Primary Examiner — Kelley Donnelly*(74) Attorney, Agent, or Firm* — Leanne Taveggia Farrell; Westman, Champlin & Koehler, P.A.(57) **CLAIM**

The ornamental design for a display unit, as shown and described.

DESCRIPTION

FIG. 1 is a perspective view of a display unit with environment showing our new design;

FIG. 2 is a perspective view of FIG. 1 without environment;

FIG. 3 is a front view of FIG. 2;

FIG. 4 is a back view of FIG. 2;

FIG. 5 is a left side view of FIG. 2, the right side view being a mirror image; and,

FIG. 6 is a top view of FIG. 2.

The broken lines shown in the drawings are included for purposes of illustrating environment or portions of the display unit and form no part of the claimed design.
